LIFTING JACK

Sidney W. Jordan, Cleveland, Ohio

Application June 20, 1936, Serial No. 86,227

5 Claims. (Cl. 254—100)

This invention relates to lifting jacks of the screw type and has for its object to provide improved means whereby the jack-block can be readily and quickly adjusted to any desired height upon the jack-screw by disengaging the threads, and then the threads can be quickly engaged and held in engagement by the weight of the object being lifted. Also the jack can be separated and its parts packed in small space. There are no small or loose parts liable to become lost and the whole device can be cast or made at small cost.

One form of the invention is illustrated in the accompanying drawing in which—Figure 1 is a side elevation of the rear end of an automobile with the jack in operative position under the bumper; Fig. 2 is a vertical section of the jack block showing the jack-screw in locked position within the block; Fig. 3 is an enlarged sectional view of the block with a fragment of the jack screw shown in slidable position, as when the threads are disengaged.

Referring to the drawing, a base 10 has an upwardly projecting boss 11 and a plurality of webs 12 radiate from the top of the boss 11 to the four corners of the base 10. A jack-screw 13 has a tapered tip 14 at its lower end rounded at 15 and which is removably inserted in the socket 16 in the boss 11; and adjacent the top of the jack screw 13 is a bore 17 through which a turning rod 18 is inserted.

A screw housing or block 19 is internally threaded at the opposed ends 20 and 21 of the housing and on opposed sides only, as illustrated in Figs. 2 and 3 respectively. A smooth channel or bore 32 is drilled through the housing or block 19 in such manner as to bisect the threaded channel or bore 33. A pair of angular lugs 34 and 35 project outwardly from the jack block 19 and on opposite sides thereof adjacent the ends 20a and 21a. These lugs are presented oppositely, so the block can be reversed if desired.

In operation, the base 10 is placed on the ground in the position desired, the tapered tip 14 of the jack-screw 13 is inserted in the socket 16, the block 19 is superimposed over the top of the jack-screw and tipped as shown in Fig. 3, the block is then slipped down until one of the lugs 34 or 35 is in position under the object to be raised such as a bumper 36 of an automobile 37 as shown in Fig. 1, the block sliding easily up and down while the jack-screw 13 is in the smooth

channel or bore 32. When in the proper position, the block 19 is tipped back to the position shown in Fig. 2, the turning rod 18 is inserted in the bore 17 and the block 19 is screwed upon the jack-screw 13 as the said jack-screw is turned in the socket 16 in the base 10. The weight of the object being raised pressing down on the lug 34 or 35 locks the external threads of the jack-screw in the internal threads of the block 19 at the top and bottom of said block.

The device thus provides a very quick adjustment to set the block at the proper height on the screw, and thereafter the screw operates to raise the block and the weight while retaining the screw threads in engagement. The parts can be readily separated and packed in a small space.

I claim:

1. A jack comprising a rotatable screw, and a jack block thereon, the block having an enlarged bore with oppositely disposed thread sections at opposite ends thereof, the sections of the bore opposite the threads being enlarged to permit the block to be tilted to engage or disengage the threads from the screw.

2. A jack as in claim 1, the block having an external weight-supporting lug on the side adjacent one of the thread sections, whereby the weight holds the threads engaged with the screw.

3. A jack comprising a rotatable screw, and a jack block thereon having a bore larger than the screw, the bore having sections of half threads at opposite sides and opposite ends thereof, and tapered recesses extending from about the middle of the bore to opposite ends thereof respectively, said recesses being at the sides of the bore opposite the thread sections, whereby the block can be tilted on the screw to engage or disengage the threads therewith.

4. A jack comprising a rotatable screw, and a slidably adjustable jack-block thereon, the block having an enlarged bore permitting it to be slid along the screw, the bore having mutilated thread sections oppositely presented at opposite ends thereof, said thread sections being engageable with the screw, or disengageable therefrom, by tilting the block.

5. A jack as in claim 4, the block having a projecting external lug substantially opposite one of said thread sections.
